(57) **CLAIM**

I claim the ornamental design for an apparatus for recording and transmitting of information, as shown and described.

DESCRIPTION

FIG. 1 is a front view of the apparatus for recording and transmitting of information;
FIG. 2 is a rear view of the apparatus for recording and transmitting of information; and
FIG. 3 is a first side view of the apparatus for recording and transmitting of information;
FIG. 4 is a second side view of the apparatus for recording and transmitting of information;
FIG. 5 is a bottom view of the apparatus for recording and transmitting of information;
FIG. 6 is a top view of the apparatus for recording and transmitting of information; and,
FIG. 7 is a perspective view of the apparatus for recording and transmitting of information.

CERTIFICATE OF CORRECTION

PATENT NO. : D659,668 S
APPLICATION NO. : 29/400846
DATED : May 15, 2012
INVENTOR(S) : Manfred Neumann

Page 1 of 1

It is certified that error appears in the above-identified patent and that said Letters Patent is hereby corrected as shown below:

On the Title Page, item (73) of the issued patent under "Assignee": I+Me Actia Informatik und Mikro-Elektronik GmbH (Braunschweig, DE) is changed to I+Me Actia Informatik und Mikro-Elektronik GmbH (Braunschweig, DE).

Signed and Sealed this
Twenty-third Day of October, 2012

David J. Kappos
Director of the United States Patent and Trademark Office
